US0D1011128S

(12) **United States Design Patent** (10) **Patent No.:** **US D1,011,128 S**
(45) **Date of Patent:** **** Jan. 16, 2024**

(54) **MIXING BOWL COVER**

(71) Applicant: **Shenzhen Longaiwen Electronic Commerce Co., Ltd.**, Shenzhen (CN)

(72) Inventor: **Yilong Ning**, Shenzhen (CN)

(73) Assignee: **SHENZHEN LONGAIWEN ELECTRONIC COMMERCE CO., LTD.**, Shenzhen (CN)

(**) Term: **15 Years**

(21) Appl. No.: **29/821,268**

(22) Filed: **Dec. 29, 2021**

(51) **LOC (14) Cl.** **07-02**

(52) **U.S. Cl.**

USPC **D7/391**

(58) **Field of Classification Search**

USPC D3/202, 318, 302; D7/302, 303, 305, D7/313, 314, 317, 318, 319, 321, 387, D7/391, 392, 392.1, 396.1, 396.2, 396.4, D7/396.5, 500, 502, 507, 509, 510, 511, D7/514, 532, 533, 536, 538, 541, 543, D7/546, 549, 601, 602, 608, 609, 610, D7/612, 615, 619.1, 622, 701, 702, 703, D7/705, 707, 708, 629, 553.3, 553.4, 505, D7/553.6, 554.2, 557; D9/428, 429, D9/435-454, 761, 434, 456, 425, 737; D10/64

CLAIM

The ornamental design for a mixing bowl cover, as shown and described.

DESCRIPTION

FIG. 1 is a perspective view of a mixing bowl cover showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view thereof.

1 Claim, 9 Drawing Sheets
